UNITED STATES PATENT OFFICE

ARNOLD GULDEMAN, OF PATERSON, NEW JERSEY, ASSIGNOR TO I. A. HALL & CO., OF PATERSON, NEW JERSEY, A FIRM COMPOSED OF ALICE VAN GIESON, VAUGHN S. AND MARY HALL, ALBERT H. MOREHEAD, SARAH A. ROE, AND MARY S. WARBURTON

SHUTTLE

Application filed April 15, 1931, Serial No. 530,160.

For a proper understanding of the principal object of this invention it is first necessary to consider that there are two general classes of looms now in use, it wit, commonly known as automatic and non-automatic. It is next necessary to recall that in the automatic loom the shuttle is threaded by entry of the weft or filling sidewise of itself into the tensioning means of the shuttle, whereas in the non-automatic shuttle the tensioning means is threaded by entry of the filling lengthwise of itself, as by a threading hook. It is finally necessary to recognize that tensioning means of the first type has not as yet been so devised that it can be reliably used, with maintenance of the proper tension and without undue breakage of filling, on all kinds of filling. Where certain silk or other delicate fabrics are being woven, for example, such tensioning means has quite limited possibilities of successful use.

If, then, a manufacturer has some looms of the automatic type and some of the non-automatic type he cannot use shuttles adapted for the automatic looms in looms of the non-automatic type if in the latter looms he wishes to weave fabrics whose quality requires that the filling thereof be subject to tensioning means of the second type. Consequently each class of looms has its own equipment of shuttles, one with one and the other with the other type of tensioning means. But there are not only two stocks of shuttles; there must also be two stocks of quills to suit them (with the additional expense of winding both stocks of quills), as will now appear: In an automatic loom shuttle the quill is held in place therein by the mere grip of two stout gripping jaws acting upon the butt of the quill and into and out of the grip of which the quill is moved by the transverse thrustwise action of a sufficiently powerful instrumentality of the loom. In a non-automatic loom shuttle the quill is bored and telescoped onto a spindle which is pivoted at its butt so that it may be shifted, pivotally, to projecting relation to the shuttle for receiving or delivering the quill by hand. Bored quills to suit either of these two kinds of shuttles might be used ex-

cept that the mentioned jaws of the automatic loom shuttle are, as indicated, necessarily very strong in order to hold the quill effectively, and to use them in shuttles operating in the non-automatic way is out of the question because many weavers do not have the hand strength necessary to overcome the grip of the jaws in entering or removing the quills, and repeatedly performing this operation by hand during a day would be practically impossible in any case.

Given, then, a weaving plant having the two classes of looms and desiring to have one stock of quills and such usable in the shuttles of both classes of looms interchangeably, whereby to eliminate the expense of two stocks of quills and the duplicate winding thereof, my principal object is to provide a non-automatic loom shuttle which will receive and properly hold a bored quill suited to shuttles for automatic looms and into or from which the weaver can without special exertion or fatigue introduce or remove a quill. Other objects will appear hereinafter.

The drawings show two forms of a shuttle embodying the invention, Figs. 1 to 4 one form and Figs. 5 to 8 the other.

Fig. 1 is a plan of one form, partly in section;

Fig. 2 a longitudinal vertical section thereof;

Fig. 3 a plan of the clip;

Fig. 4 a side elevational of the tongue;

Fig. 5 a plan of the other form, partly in section;

Fig. 6 a longitudinal horizontal section thereof, partly in plan;

Fig. 7 a longitudinal vertical section thereof; and

Fig. 8 a side elevation of the slip and spindle.

Referring, first, to Figs. 1 to 4:

The shuttle body 1 has the usual cavity 2 for the quill 3 and extending from one end of this cavity the mortise 4 for the quill mounting constructed as follows:

5 designates two stout spring jaws which are to grip the butt of the quill between them and are grooved or serrated at their free ends

to receive the rings 3a which as usual embrace the butt of the quill, which is of the type used in automatic shuttles and will be understood to be axially bored; these jaws are related as 5 the branches of a fork and they may be formed from a single strip of metal bent on itself with a sharp bend so that the portions 5b of the fork near the bend are substantially parallel and spaced from each other but ap- 10 preciably closer together than their free or quill-gripping portions 5a. Between the portions 5b of the jaws and projecting into the space between their quill-gripping portions 5a is a flat metal tongue 6 which is piv- 15 oted to portions 5b at 7. The trifurcate or three-pronged clip thus formed is entered to the mortise, which it snugly fits, and under its overhangs at 4a from the cavity 2, and it is held in place by what I term two pins 8 and 9, 20 one of which, as 8, may be a plain pin and the other, 9, a screw or bolt equipped with a nut 9a, they being driven through the shuttle body and clip transversely. When pin 9 is removed the tongue may be elevated on its 25 pivot to the dotted-line position in Fig. 2, and for this purpose whereas the aperture therein for pin 9 is a hole 11 the aperture for pin 8 is a rearwardly open notch 10. At the free end of the tongue is pivoted on a removable 30 pin 12a the forked butt of the spindle 12.

The bored quill is adapted to be slipped, telescopically, onto this spindle when the latter is raised (dotted lines, Fig. 2) and when the spindle with the quill thereon is de- 35 pressed the quill is confined both against end- wise movement on the spindle and against rise pivotally with the spindle by the gripping action of the jaws of the clip. Notwith- standing the strong gripping action of the 40 jaws to prevent inadvertent movement of the spindle when sheathed or depressed in the cavity and when the shuttle is in action, due to the lever-nature of the spindle the elevat- 45 ing or depressing thereof to clear the quill from or force it between the jaws can be man- ually effected by the weaver with ease.

On removal of pin 9 and elevation of tongue 6 so that it projects from the space of the fixed shuttle structure with its pin 12a 50 clear the pin (which is otherwise confined between the jaws of the clip) may be removed to change the spindle.

The forward lower corner of the tongue and the floor of the mortise afford a stop to 55 the spindle on depressing the same (Fig. 3).

Figs. 5 to 8:

If in some instances, as in large shuttles carrying heavy quill loads, it is desired to 60 augment the gripping action of the jaws against possible rise of the spindle, a plate- 65 spring 13 may be employed. This is formed to fit a recess 14 at the top of the mortise and it bears at one end on the shuttle body and at the other end on the spindle butt, being held down under adjustable pressure between its

ends by a screw 15 which penetrates the clip (specifically the tongue 6) and is provided with a nut 15a. This spring serves effectively to hold the spindle in either the raised or depressed position. In this case the tongue is not, as shown, elevatory, so as to permit removal of the spindle without removal of both pins 8 and 9 and the plate-spring. This form of the invention further permits quills, 70 cops or other wound cores to be used in the shuttle which are too small at the butt to be gripped by the jaws 5 so that the spindle when the shuttle is in use would be held depressed by their gripping action.

Having thus fully described my invention 80 what I claim is:

1. In combination, a shuttle body having a space therein open at one longitudinal face thereof, a trifurcate structure held in said body and having its prongs in said space and the two outer prongs on opposite sides of a plane extending lengthwise of the shuttle and through said face and forming wound-core-gripping jaws, and a spindle pivoted at its butt to the intermediate prong to move in 90 said plane into and out of said space and into and out of position where a core therein will be gripped by the jaws.

2. In combination, a shuttle body having a space therein open at one longitudinal face thereof, a pair of fixed members in said body having spaced wound-core-gripping jaws in said space and on opposite sides of a plane extending lengthwise of the shuttle and through said face, a tongue held between said members, and a spindle pivoted at its butt to the tongue to move in said plane into and out of said space and into and out of 95 position where a core therein will be gripped by the jaws.

3. In combination, the fixed structure of a shuttle, said structure having a space therein open at one longitudinal face thereof, a tongue arranged in said structure and having a portion thereof in said space, and a spindle pivoted to said portion of the tongue to move in a plane extending lengthwise of the shuttle and through said face, said tongue being movable in said structure to bring its said portion exterior of said space but normally releasably held against such movement and the spindle being disconductive from said tongue when said portion thereof is exterior of said space but being confined by said structure against disconnection from the tongue when said portion is within said space.

4. In combination, the fixed structure of a shuttle, said structure having a space therein open at one longitudinal face thereof, a tongue arranged in said structure and having a portion thereof in said space, and a spindle pivoted to said portion of the tongue to move in a plane extending lengthwise of the shuttle and through said face, said tongue being pivotally movable in said structure to bring its 120 125 130

said portion exterior of said space but normally releasably held against such movement and the spindle being disconnection from said tongue when said portion thereof is exterior 5 of said space but being confined by said structure against disconnection from the tongue when said portion is within said space.

5. In combination, a shuttle body having a wound-package cavity open at one longitudinal face thereof, wound-package-holding means secured in said body and including co-acting package-gripping portions projecting into said cavity on opposite sides of a plane extending lengthwise of the shuttle and 10 through said face, a spindle on which a wound package is adapted to be telescopically placed pivotally movable in said plane, either into sheathed position in the cavity or 15 into position to project therefrom, and means 20 in the cavity affording pivotal support for this spindle.

6. In combination, the fixed structure of a shuttle, said structure having a wound-package cavity open at one longitudinal face 25 thereof and spaced means to grip a wound package when placed within the cavity and arranged on opposite sides of a plane extending lengthwise of the shuttle and through said face, and a spindle on which the package 30 is to be telescopically placed arranged in said cavity with its butt between and spaced from said means, the spindle being pivoted to said structure to move in said plane either 35 into sheathed position in the cavity or into position to project therefrom.

In testimony whereof I affix my signature.
ARNOLD GULDEMANN.
